Primary Examiner—Jeffrey Asch
Attorney, Agent, or Firm—Marshall, O'Toole, Gerstein, Murray & Borun**[57] CLAIM**

The ornamental design for a CD rack, as shown and described.

DESCRIPTION

FIG. 1 is a left, front perspective view of a CD rack showing my new design.

FIG. 2 is a front, plan view of the CD rack of FIG. 1.

FIG. 3 is a left side view of the CD rack of FIG. 1.

FIG. 4 is a right side view of the CD rack of FIG. 1.

FIG. 5 is a top view of the CD rack of FIG. 1.

FIG. 6 is a back plan view of the CD rack of FIG. 1; and, FIG. 7 is a bottom view of the CD rack of FIG. 1.

The broken line showings throughout the views are for illustrative purposes only and form no part of the claimed design.
